(57) **CLAIM**

The ornamental design for a jump shot trainer, as shown and described.

DESCRIPTION

FIG. 1 is a top front perspective view of a jump shot trainer showing my new design;

FIG. 2 is a bottom rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom elevational view thereof.

1 Claim, 8 Drawing Sheets
